To all whom it may concern:

Be it known that I, Elmer C. Kiekhaefer, a citizen of the United States, residing at Cedarburg, in the county of Ozaukee and State of Wisconsin, have invented a new, original, and ornamental Design for an Outboard Motor, of which the following is a specification, reference being had to the accompanying drawings, forming part thereof.

In the drawings:

Fig. 1 is a perspective view of the outboard motor embodying my new design;

Fig. 2 is a front elevation of the outboard motor shown in Figure 1; and

Fig. 3 is a top plan view of the outboard motor shown in Fig. 1.

The essential features of my design reside in the portions shown in full lines.

I claim:

The ornamental design for an outboard motor, as shown and described.
